US0D1030191S

(12) United States Design Patent (10) Patent No.: US D1,030,191 S
(45) Date of Patent:  Jun. 11, 2024

(54) BRASSIERE

(71) Applicant: Reebok International Limited,
Altrincham (GB)

(72) Inventor: Heather Danila, Boston, MA (US)

(73) Assignee: Reebok International Limited,
Altrincham (GB)

() Term: 15 Years

(21) Appl. No.: 29/851,309

(22) Filed: Aug. 26, 2022

(51) LOC (14) Cl. 02-01

(52) U.S. Cl.

USPC D2/706

(58) Field of Classification Search

USPC D2/700-703, 706, 731, 736-738

CPC A41C 3/00; A41C 3/0057

See application file for complete search history.
